UNITED STATES PATENT OFFICE.

ANDREW A. SCHRAMM, OF PHILADELPHIA, PENNSYLVANIA.

PARTITION CONSTRUCTION FOR FILING-CABINETS.

1,274,308.

Specification of Letters Patent. Patented Aug. 6, 1918.

Application filed April 14, 1917. Serial No. 161,941.

To all whom it may concern:

Be it known that I, ANDREW A. SCHRAMM, a citizen of the United States, residing at Philadelphia, in the county of Philadelphia 5 and State of Pennsylvania, have invented certain new and useful Improvements in Partition Construction for Filing-Cabinets, of which the following is a specification.

My invention consists of improvements in 10 partition construction for filing cabinets. One object of my invention is to provide a detachable metallic partition construction which will be adapted for use in filing cabinet drawers of various sizes and styles.

Another object is to so make my invention 15 that its construction will require a comparatively small amount of material, and so that it can be cheaply manufactured.

A further object is to make my invention 20 of a durable and simple construction.

These objects, and other advantageous ends 25 which will be described hereinafter, I attain in the following manner, reference being had to the accompanying drawings in which—

Figure 1 is a sectional elevation taken longitudinally through a filing cabinet drawer of a type now in common use and showing how my invention provides de- 30 tachable partitions and removable auxiliary sides therefor.

Fig. 2 is a section on the line 5—5 of Fig. 1.

Fig. 3 is a face view of one of the de- 35 tachable partitions illustrated in Figs. 1 and 2.

Fig. 4 is a top plan view of the drawer and parts shown in Fig. 1.

Fig. 5 is a face view of one of the auxil- 40 iary drawer sides illustrated in Figs. 1 to 4 inclusive, developed in a flat plane.

Fig. 6 is a perspective view of one of said auxiliary drawer sides bent and ready for use.

Fig. 7 is a perspective view of a slotted channel rack and designed to be inserted 45 within the bottom of the drawer illustrated in Figs. 1, 2, and 4.

Referring to the drawings, a drawer 19 50 has a front 20, a rear 21, and sides 22 and 23. The drawer thus illustrated is one having the general construction of filing drawers which include a slot 24 extending throughout the length and centrally of the bottom 25, said slot usually being formed to provide space for a retaining rod designed

to secure spacers or partitions within the drawer, said spacers or partitions usually having holes adjacent their bottoms through which the rod extends so that the latter prevents the removal of said spacers from the drawer until the rod has been slid longitudinally to free said partitions.

In applying my invention to a drawer of this type, I employ the slot 24 as a receptacle for a channel rack 26, said channel rack having its upper surface flush with the upper surface of the bottom 25. This channel rack 26 has transversely extending slots 27 which are spaced apart as clearly illus- 70 trated in Figs. 4 and 7.

Auxiliary drawer sides 28 and 29 are each made from a piece of sheet metal such for example as shown in Fig. 5. This metal is preferably stamped or cut from a long strip 75 and has a row of holes 30 which are spaced apart the distances between the holes being similar to the distance between the slots 27 in the channel rack 26.

The sheet of metal shown in Fig. 5 is bent 80 along the lines 31 and 32, such bent position being shown in Figs. 1, 2, and 6. The lower edge 33 of each of the auxiliary sides 28 and 29 is designed to rest upon the bottom 25 of the drawer, the portions 34 being positioned adjacent the inner surfaces of the drawer sides 22 and 23.

The portions 34 of the auxiliary drawer sides are made higher than the height of the highest sides of drawers now in common use, 90 so that the ledges 35 which are formed by the bending of the auxiliary sides as above noted, will be positioned above the upper edges of the sides of the drawer proper.

The portions 36 of the auxiliary sides 95 which depend from the ledges 35, are de- signed to straddle the upper portions of the drawer sides 22 and 23, the width of said portions 36 being such that they depend to such level that they will embrace the upper edge portions of the sides of the most shallow drawer that is now in common use, thus my auxiliary drawer sides are capable of embrac- 100 ing the sides of drawers of various heights.

Partitions 37 are detachably connected to the auxiliary sides 28 and 29, and to the channel rack 26 in the following manner:— Each partition 37 is preferably made of sheet metal and has a tongue 38 designed to fit any of the slots 27 in the channel rack 26. The upper edge of each of the partition

37 is turned to form a hollow beading 39, said beading extending entirely across the top of the partition and at its ends providing a housing for shanks 40 of hooks 41. 5 The depending ends 42 of the hooks 41 are designed to engage respective holes 30 in the ledges 35 provided on the auxiliary sides 28 and 29, it being noted that said holes 30 register with the slots 27 in the channel rack 10 26. The partitions are thus securely held between the drawer sides and at their bottoms by the engagement of the tongues 38 in the slots 27.

Any number of the partitions may be used 15 within a drawer, and the spacing of the holes and slots may be such as to suit the requirements of the drawer.

As illustrated in Figs. 1, 5 and 6, the ends of the auxiliary sides flare downwardly. 20 This permits the auxiliary sides to be inserted in extremely short drawers, since it requires but a small amount of the metal to be removed from the ends of the auxiliary sides if it is necessary to cut down on the 25 length thereof.

It will thus be noted that my invention is adapted for use in connection with various sized drawers, and drawers of various types.

While I have described my invention as 30 taking a particular form, it will be understood that the various parts of my invention may be changed without departing from the spirit thereof, and hence I do not limit myself to the precise construction set forth, 35 but consider that I am at liberty to make such changes and alterations as fairly come within the scope of the appended claims.

Having thus described my invention, what I claim as new and desire to secure by Letters Patent is:

1. The combination with a drawer, of auxiliary sides designed to embrace the sides of the drawer and having portions adapted to rest upon the bottom of the drawer adjacent 45 side surfaces thereof, and other portions adapted to extend over the top edges of the drawer sides and embrace the opposite surfaces of said latter sides, said first portions of the auxiliary sides being of greater height than the sides of the drawer to provide space between the upper edges of the drawer sides and said second portions of the auxiliary sides, substantially as described.

50 2. The combination with a drawer, of auxiliary sides designed to embrace the sides of the drawer and having portions adapted to rest upon the bottom of the drawer between the sides thereof, and other portions adapted to extend over the top edges of the drawer sides and embrace the outer surfaces of said latter sides, said first portions of the auxiliary sides being of greater height than the sides of the drawer to provide space between the upper edges of the drawer sides

and said second portions of the auxiliary sides, substantially as described.

3. The combination with a drawer, of removable auxiliary sides having ledges formed on the tops thereof and holes extending through said ledges, means on the bottom of said drawer providing slots, a detachable partition having a tongue capable of engaging any of said slots, clips secured to said partition, shanks held in frictional 75 engagement between the clips and the partition, said shanks having outer hooked ends depending therefrom designed to enter the holes in said ledges, substantially as described.

4. The combination with a drawer having permanent sides, of auxiliary sides designed to embrace the sides of the drawer and having edge portions adapted to freely rest upon the bottom of the drawer between the sides 85 thereof, and other portions adapted to extend over the top edges of the drawer sides and freely embrace the outer surfaces of said latter sides, a partition adapted to be positioned transversely between the auxiliary sides, and means for detachably connecting the partition to the auxiliary sides, 90 substantially as described.

5. The combination with a drawer, of auxiliary sides designed to embrace the sides of the drawer and having portions adapted to rest upon the bottom of the drawer between the sides thereof, and other portions adapted to extend over the top edges of the drawer sides and embrace the outer surfaces of said 100 latter sides, a partition adapted to be positioned transversely between the auxiliary sides, said second portions of the auxiliary sides, having holes therein spaced apart throughout their lengths, and means on said 105 partition for entering any of the oppositely disposed holes on the auxiliary sides, substantially as described.

6. The combination with a drawer, of a rack mounted on the bottom of the drawer 110 and having a row of transversely extending slots, auxiliary sides designed to embrace the sides of the drawer and to rest upon the bottom of the drawer between the sides of said drawer, said auxiliary sides at their 115 top being provided with ledges having rows of holes formed therein, a partition having a tongue designed to engage any of the slots in the rack, and means on said partition designed to depend through the holes 120 in said ledges of the auxiliary sides, substantially as described.

7. The combination with a drawer, of auxiliary sides designed to embrace the sides of the drawer and having portions adapted to 125 freely rest upon the bottom of the drawer between the sides thereof, and other portions adapted to extend over the top edges of the drawer sides and freely embrace the outer surfaces of said latter sides, said first 130

portions having their ends extending at an incline, substantially as described.

8. The combination with a drawer, of a rack mounted on the bottom of the drawer and having a row of transversely extending slots, auxiliary sides designed to embrace the sides of the drawer and to rest upon the bottom of the drawer between the sides of said drawer, said auxiliary sides at their top being provided with ledges having rows of holes formed therein, a partition having a tongue designed to engage any of the slots in the rack, means on said partition designed to depend through the holes in said ledges of the auxiliary sides, said auxiliary sides being higher than the sides of the drawer to provide chambers above the upper edges of the drawer for the reception of said latter means on the partition, substantially as described.

9. The combination with a drawer, of a rack mounted on the bottom of the drawer and having a row of transversely extending slots, auxiliary sides designed to embrace the sides of the drawer and to rest upon the bottom of the drawer between the sides of said drawer, said auxiliary sides at their top being provided with ledges having rows of holes formed therein, a partition having a tongue designed to engage any of the slots in the rack, means on said partition designed to depend through the holes in said ledges of the auxiliary sides, said auxiliary sides having portions depending from the ledge and designed to engage the outer surfaces of the sides of the drawer, substantially as described.

ledges of the auxiliary sides, said auxiliary sides being higher than the sides of the drawer to provide chambers above the upper edges of the drawer for the reception of said latter means on the partition, said auxiliary sides having their ends flared downwardly, substantially as described.

10. The combination with a drawer, of a rack mounted on the bottom of the drawer and having a row of transversely extending slots, auxiliary sides designed to embrace the sides of the drawer and to rest upon the bottom of the drawer between the sides of said drawer, said auxiliary sides at their top being provided with ledges having rows of holes formed therein, a partition having a tongue designed to engage any of the slots in the rack, means on said partition designed to depend through the holes in said ledges of the auxiliary sides, said auxiliary sides being higher than the sides of the drawer to provide chambers above the upper edges of the drawer for the reception of said latter means on the partition, substantially as described.

In testimony whereof I have signed my name to this specification in the presence of two subscribing witnesses.

ANDREW A. SCHRAMM.
